MOVING PICTURE CAMERA

Fritz Albert Blank, New Rochelle, N. Y.

Application November 5, 1957, Serial No. 48,347

Term of patent 14 years

(Cl. D61—1)

Fig. 1.

Fig. 2.

Fig. 1 is an elevational perspective view of the moving picture camera embodying my new design, showing the front, the top and left side of the device; and

Fig. 2 is a similar elevational perspective view of the moving picture camera illustrated in Fig. 1 showing the back, the top and the right side thereof.

I claim:

The ornamental design for a moving picture camera, as shown.
